UNITED STATES PATENT OFFICE

WILLIAM O. HORN, OF NEW YORK, N. Y.

DESIGN FOR A NECKWEAR-RETAINER.

SPECIFICATION forming part of Design No. 31,727, dated October 24, 1899.

Application filed September 28, 1899. Serial No. 731,981. Term of patent 3 $\frac{1}{2}$ years.

To all whom it may concern:

Be it known that I, WILLIAM O. HORN, a citizen of the United States, residing in the city, county, and State of New York, have 5 invented and produced a new and original Design for Neckwear-Retainers, of which the following is a specification, reference being had to the accompanying drawings, forming part thereof.

10 The leading feature of my design for a neckwear-retainer is a plate with hooks rising from the lower portion thereof on opposite sides of the center thereof.

15 Figures 1 and 2 represent perspective views of opposite faces of a neckwear-retainer embodying my design. Fig. 3 represents a section on line $x-x$, Fig. 1.

In the drawings, A designates the plate of

a neckwear-retainer, and B designates hooks which rise from the lower portion of said plate 20 on opposite sides of the center thereof, the limbs of said tongues appearing, respectively, on the front and rear faces of said plate.

C designates tongues which depend from the inner limbs of the hooks between the plate 25 and outer limbs of the hooks.

Having thus described my invention, what I claim as new, and desire to secure by Letters Patent, is—

The design for a neckwear-retainer substantially as shown and described.

W. O. HORN.
